UNITED STATES PATENT OFFICE.

HAROLD EDWARD SHERWIN HOLT, OF FARNBOROUGH, ENGLAND.

SAFETY-RAZOR.

1,079,174.

Specification of Letters Patent.

Patented Nov. 18, 1913.

Application filed November 18, 1911. Serial No. 661,022.

To all whom it may concern:

Be it known that I, HAROLD EDWARD SHERWIN HOLT, a subject of the King of Great Britain and Ireland, residing at "The 5 Grange," Farnborough, Hampshire, England, have invented certain new and useful Improvements in Safety-Razors, of which the following is a specification.

This invention for improvements in razors 10 relates to folding razors in which a thin blade is supported by end tension on a holder provided with a guard, and has for its object to provide means for applying the end tension to the blade, also for securing a 15 guard and stropping shield to the blade holder.

Now according to this invention the supporting back or holder is provided with two pins or lugs for holding the blade, and the 20 blade is provided at its ends with two holes for engaging the lugs. One of these lugs is fixed rigidly, while the other is mounted eccentrically on a short lever by means of which the tension is applied to the blade. 25 The guard is either made in one piece with the holder or is detachable as hereinafter described.

In mounting the blade on its back the 30 lever is so placed that the lugs approach one another, in which position the blade fits over the lugs after which the moving of the lever draws the lugs apart, and puts the blade in tension.

The back forming the support for the 35 blade is either made in the known manner with a row of prongs or fingers on either side forming the guard, or the guard is made removable, and is secured to the back by the same pins or lugs on the blade.

40 For the purpose of stropping the razor the back or blade holder supports a shield which covers the one edge of the blade while the other edge is being stropped.

The accompanying sheets of illustrative 45 drawings show two forms of the invention by way of example.

Figure 1 is an elevation of an open razor constructed according to the present invention. Fig. 2 is a reversed elevation of the 50 same. Fig. 3 is an elevation looking on the edge of the blade. Fig. 4 is a transverse section of the blade and back, Fig. 5 is a plan of Fig. 2. Figs. 6 and 7 are elevation and cross section respectively, of a modified 55 form of blade holder for use with a removable guard plate. Figs. 8 and 9 are face and

edge views of the removable guard, and Figs. 10 and 11 are front and end views respectively of the stropping shield.

Referring to Figs. 1 to 5 the blade *a* is 39 mounted between two pins *b c* on the back *d*. The pin *b* is fixed while the pin *c* is mounted eccentrically on the back, and is provided with a short lever *e*. The blade is provided with two holes at its ends by which it is held 45 on the pins *b c*, these latter having slightly enlarged heads.

The back *d* is made in the form of a guard with a series of fingers on either side.

In mounting the blade on the back the 70 lever is so turned as to cause the eccentric pin to approach the fixed pin, when the blade is put in place and the lever turned again to apply the necessary tension to the blade.

In the modified form of construction 75 shown in Figs. 6 to 9 the back *d* instead of being provided with integral guard teeth is arranged to hold a detachable guard plate *f* which is conveniently stamped out 80 of sheet metal. The guard plate is slit or cut at one end to enable a narrow strip *g* to be bent up out of the plane of the guard plate to form a spring, and is also provided with slots *h* adapted to be passed over the 85 pins or lugs *b* on the holder *d*.

When placing the guard on the holder the pins *b* are passed through the wide ends of the slots *h*, after which the guard is slid longitudinally to cause the pins to engage 90 the narrow parts of the slots. After the guard has been placed in position the blade is placed over it, and secured as before described.

The stropping shield *i* shown in Figs. 10 95 and 11 consists of a plate curved along one edge *j* as shown, the curved edge covering one edge of the blade when it is being stropped, and also insuring the blade lying on the strop at the required angle. Slots *h'* 100 similar to the slots in the guard are formed in the shield, and a spring portion *g'* is also bent up on the shield, the shield being held on the support *d* in the same manner as the guard *f*.

105 What I claim, and desire to secure by Letters Patent is:—

1. A razor of the character described comprising a blade with holes in opposite ends, a blade holder or support, a pin fixed in 110 one end of the support, and adapted to engage one end of the blade, a second pin

mounted to rotate axially in the support and provided with an eccentric portion adapted to engage the other end of the blade, and means for axially rotating the pin to apply end tension to the blade said pins engaging the sides of the holes in the blade nearest the respective blade ends when the blade is secured to the holder.

2. A razor of the character described comprising a blade with holes in opposite ends, a blade holder or support, a pin fixed in one end of the support, and adapted to engage one end of the blade, a second pin mounted to axially rotate in the support and provided with an eccentric portion adapted to engage the other end of the blade, and a short lever fixed to the pin and capable of axially rotating the pin to secure or release the blade said pins engaging the sides of the holes in the blade nearest the respective blade ends when the blade is secured to the holder.

3. A razor of the character described comprising a blade with holes in opposite ends, a blade holder or support, a pin fixed in one end of the support, and adapted to engage one end of the blade, a second pin mounted to rotate in the support and provided with an eccentric portion adapted to engage the other end of the blade, means for rotating the pin to apply end tension to the blade, and a removable guard interposed between the blade and blade holder, and provided with openings taking over the blade tensioning pins said pins engaging the sides of the holes in the blade nearest the respective blade ends when the blade is secured to the holder.

In testimony whereof I have affixed my signature, in presence of two witnesses.

HAROLD EDWARD SHERWIN HOLT.
